UNITED STATES PATENT OFFICE.

PHILIP A. MYERS, OF ASHLAND, OHIO, ASSIGNOR TO F. E. MYERS AND BROTHER, OF ASHLAND, OHIO, A COPARTNERSHIP.

WORKING HEAD FOR POWER-PUMPS.

No. 928,284.

Specification of Letters Patent.

Patented July 13, 1909.

Application filed December 26, 1906. Serial No. 349,448.

To all whom it may concern:

Be it known that I, PHILIP A. MYERS, a citizen of the United States, residing at Ashland, in the county of Ashland and State of Ohio, have invented certain new and useful Improvements in Working Heads for Power-Pumps, of which the following is a specification, reference being had therein to the accompanying drawings.

- 10 The present invention relates to working heads for power pumps and has for its object the production of a working head for a pump of this character of such a construction that the several parts can be readily moved to 15 permit of access to the interior of the head, whereby the working parts can be removed without disconnecting the discharge pipe from the base, without loosening the fastenings which secure the base to the platform, 20 or other supporting structure and without disconnecting the driving mechanism.

With this object in view my invention consists of certain novel features of construction hereinafter described, and more fully 25 pointed out in the claims.

In the accompanying drawings, Figure 1 is a side elevation of a working head embodying my invention; Fig. 2 is a vertical sectional view of the same; Fig. 3 is a top 30 plan view of the same showing the driving wheels and the gears in section; Fig. 4 is a front elevation of a portion of the working head, showing the cross head in detail; Fig. 5 is a plan view of the base, with the cap 35 removed; Fig. 6 is a sectional detail view of the supporting plate or bushing through the suction pipe; Fig. 7 is a vertical sectional view of a portion of the base of a modified form of the device; Fig. 8 is a top plan view 40 of the modified form; and Fig. 9 is a front elevation of the upper portion of the same.

In these drawings I have illustrated the preferred form of my invention, in which the reference numeral 1 indicates the usual 45 base, which is provided with a flange 2 for securing the same to a platform or supporting structure. The base is provided on its rear side with a bearing lug 3, in which is journalized a driving shaft 4, extending beyond the base at either end thereof and provided at one end with a suitable driving pulley 5 and an idler 6 and at its other end with a pinion 7 secured thereon by a suitable collar 8. The front or opposite side of the base 55 is also provided with a bearing lug 9, in

which is journalized an operating shaft 10, extending beyond the base at either end thereof and provided at one end with a gear 11 meshing with the pinion 7, and provided with a wrist pin 12 on which is mounted the lower end of a connecting rod 13, the upper end of which is secured to one end of the cross head 14. The opposite end of the operating shaft 10 is provided with a crank arm 15 having a wrist pin 16, on which is mounted the lower end of a connecting rod 17, the upper end of which is secured to the corresponding end of the cross head 14. The cross head 14 is provided with vertical bearings 18, adapted to receive the guide rods 19 and to reciprocate vertically thereon. The guide rods 19 are rigidly secured near their lower ends in the opposite ends of a substantially semicircular supporting frame 20, which is pivotally connected at its rear or central part to a suitable bearing lug 21, extending rearwardly from the base 1, by means of a pivot pin 22. Those portions of the guide rods 19 which extend beyond the supporting frame 20 are screw-threaded, 80 as shown at 23, and are adapted to extend through the oblong apertures 24 formed in the lugs or ears 25 on the base 1. The threaded ends 23 of the guide rods 19 are provided beneath the lugs 25 with suitable nuts 26, whereby the supporting frame and guide rods are rigidly secured in their normal or vertical position. The cross head 14 is provided with a central enlarged portion 27 having a vertical aperture 28 adapted to receive the upper end of the pump rod 29 and provided with suitable means, such as the screw threads 30, to prevent the vertical movement of said pump rod within the cross head and render the pump rod laterally detachable therefrom. In order that the pump rod may be readily separated from the cross head, the latter is formed in two parts, as shown, the dividing line extending vertically through the aperture 28 and dividing the 90 same near its center. The detached portion 31 of the cross head is of substantially the same length as the enlarged portion 27 thereof and is rigidly secured to the cross head proper by means of suitable bolts 32.

The base 1 is provided near its upper end with an enlarged portion 33 forming a shoulder 34 in the interior of the base adapted to support the bushing or plate 35 which is provided with a centrally arranged screw- 105

110

threaded aperture 36 which is adapted to receive the upper end of the suction pipe 37 and support the same in its proper position within the base. The bushing or plate 35 fits snugly upon the shoulder 34 and is held securely thereon by suitable means to form a water-tight joint. This bushing or plate 35 divides the enlarged portion 33 of the base from the remainder thereof and forms a chamber 38 which is provided with an outlet aperture 39, to which is connected the discharge pipe 40. The chamber 38 is closed at its upper end by a cap 41 having a central aperture 42 to permit of the passage of the pump rod 29. This aperture is preferably screw-threaded to receive the screw-threaded stuffing box 43, in which the pump rod reciprocates. The inner surface of the cap 41 is provided with a downwardly extending sleeve 44 surrounding the aperture 42 and forming a guideway for the pump rod. The sleeve 44 preferably terminates a short distance above the bushing 35 and is provided with a series of outwardly projecting arms 45 of such length that they will engage the upper surface of the bushing or plate 35 and retain the same firmly in position, when the cap 41 is in position on the upper portion of the base 1. The cap 41 is provided with a suitable packing 46 and is secured to the base 1 by means of suitable bolts 47 extending through the cap and through the flange 48, surrounding the upper edge of the base 1 and provided with nuts 50 on one end thereof. The bushing or plate 35 is provided with links or staples 49, rigidly secured thereto and extending upward to afford means for attaching the same to a cable or other hoisting means for removing the bushing and suction pipe from the well.

With the parts in their normal position, as shown in full lines in Fig. 1, when it is desired to gain access to the interior of the head to remove the working parts, or for any other purpose, the bolts 32 are loosened and the detachable portion 31 of the cross head 14 is removed, thereby allowing the screw-threaded end of the pump rod 29 to be readily removed from the aperture 28 in the cross head. The nuts 26 are then removed from the screw-threaded ends 23 of the guide rods 19 and the connecting mechanism and its supporting frame 20 can then be tilted backward by swinging the same about the pivot pin 22, the elongated apertures 24 allowing the lower ends of the guide rods 19 to free themselves from the lugs 25 of the base 1 as the frame is tilted. When the connecting mechanism and its supporting frame swing back into the position shown in dotted lines in Fig. 1, all obstructions are removed from above the base, and, by loosening the bolts 47 and removing the cap 41, free access can be had to the interior of the working head and the working

parts can be readily removed therefrom without necessitating the disconnecting of the discharge pipe or the loosening of the fastening means, whereby the base is secured to its supporting structure.

While I have shown and described a preferred form of construction for the working head it is obvious that various forms of the same may be employed without departing from the spirit of the invention. One such modification is illustrated in Figs. 7 to 9 of the drawings. In these figures the reference numeral 51 indicates the upper end of the base, the diameter of the hollow interior of the same being substantially uniform throughout its length. The base is preferably provided near its upper end with an enlarged portion 52 in which is provided a passage 53 extending from the upper edge of the base to a point below the top thereof. The upper end of the hollow base is closed by a plate 54 provided with a central aperture 55 which is surrounded by a screw-threaded boss 56 which receives the upper end of the suction pipe 57 and supports the same centrally of the hollow base. This plate is of such a diameter that it extends beyond the edge of the base and is secured thereto by suitable screws or bolts 58. The plate 54 is also provided with a suitable aperture 59 registering with the passageway 53 in the wall of the base 51. A hollow cap 60, preferably of the form known as duck-nest caps, incloses the entire upper end of the base 51 and is provided with a flange 61 which is secured to the flange 62 of the base 51 by means of suitable bolts 63. The internal diameter of the cap 60 is sufficient to allow it to fit over the edge of the plate 54, and a suitable packing is interposed between the flange 62 of the base 51 and both the plate 54 and the flange 61 of the cap. The cap 60 is also provided with a central aperture in which is mounted a stuffing box 64 which forms a bearing for the pump rod 65 which extends through the cap and into the suction pipe 57, as shown. The base 51 is provided with apertured ears 66 on which are rigidly mounted guide rods 67, preferably by screwing the lower ends thereof into the apertures 66 and providing the same with suitable jam-nuts 68 on the projecting ends thereof. The rods 67 are adapted to engage the vertical bearings 69 in the cross head 70 and form guides for said cross head. The cross head 70 is operated from the driving mechanism by means of the connecting arms 71 and serves to connect said driving mechanism with the pump rod 65, which is secured in a central aperture 72 formed in the cross head. The cross head 70 preferably consists of two parts, the line of division extending vertically through the bearing apertures 69 and the central aperture 72 and extending longitudinally of the

cross head to the extreme outer edges of the bearing apertures 69; and thence extends forward through the outer wall of the cross head, as shown at 73. The detachable portion 74 of the cross head is rigidly secured to the cross head proper by means of suitable bolts 75 or by other suitable means. When it is desired to gain access to the interior of the base 51, the bolts 75 are removed from the cross head and the detachable portion 74 thereof is removed. The body of the cross head 70 is then moved away from the guide rods 67 and the pump rod 65, thus moving the cross head out of alinement with the hollow base and permitting the ready removal of the pump rod, suction pipe and their coöperating parts. This form of base and means for supporting the suction pipe, as more clearly shown in Fig. 7, is not specifically claimed in the present application as it forms a part of the subject matter of a co-pending application for patent filed June 12, 1909, Serial Number 501,703. Thus, it will be seen that I have provided for removing quickly and easily the connecting means from a position which would interfere with the withdrawal of the pump rod and the accompanying parts to a position which will leave the course clear to effect such a withdrawal. I have here stated and described two forms of construction for this purpose. Other obvious forms may also be adopted without departing from my invention. It will further be noted that among the parts which accompany the withdrawal of the pump rod is the cap 41 or its equivalent used for closing the upper part of the bases.

I wish it to be understood that I do not desire to be limited to the exact details of construction shown and described, for obvious modifications will occur to a person skilled in the art.

Having thus fully described my invention, what I claim as new and desire to secure by Letters Patent, is:—

1. In a working head for pumps, the combination, with a base having inlet and discharge openings, a pump rod, a cross head attached to and detachable from said pump rod, and means for actuating said cross head, or guide rods on which said cross head is mounted, and a support for said guide rods movably mounted on said base, whereby said cross head may be moved out of alinement with said base.

2. In a working head for pumps, the combination, with a base having inlet and discharge openings, a pump rod, a cross head detachably connected to said pump rod, and means for actuating said cross head, of guide rods on which said cross head is mounted, and a support for said guide rods pivoted to said base, whereby said cross head may be swung out of alinement with said base.

3. In a working head for pumps, the combination, with a base having a suction pipe and a discharge opening, a pump rod, operating mechanism for said pump rod, and means for connecting said operating mechanism with said pump rod, of a substantially U-shaped supporting frame for said connecting means pivotally connected to said base, whereby said supporting frame and said connecting means may be swung out of alinement with said base, substantially as described.

4. In a working head for pumps, the combination, with a base having inlet and discharge openings, a pump rod, and a supporting frame pivotally mounted on said base at one side thereof and extending on the opposite sides of said pump rod, of guide rods rigidly secured to said frame, a cross head detachably connected to said pump rod and having guideways adapted to coöperate with said guide rods, and means for actuating said cross head, whereby upon the movement of said frame about its pivotal center said frame, said guide rods and said cross head will be moved out of alinement with said base.

5. In a working head for pumps, the combination, with a base having inlet and discharge openings, a supporting frame pivotally mounted on said base, means for rigidly securing said frame to said base, and a pump rod, of guide rods rigidly secured to said frame, a cross head connected to said pump rod and having guideways adapted to coöperate with said guide rods, and means for actuating said cross head, whereby upon the movement of said frame about its pivotal center the same and the parts carried thereby will be moved out of alinement with said base.

6. In a working head for pumps, the combination, with the base having inlet and discharge openings, lugs formed on said base having elongated apertures therein, of a supporting frame pivotally mounted on said base having apertures near the ends thereof, said apertured frame extending above said apertured lugs, guide rods rigidly secured in the apertured ends of said supporting frame, extending beyond the same and adapted to enter the elongated apertures in said lugs, means for securing said guide rods within said apertured lugs, a cross head reciprocally mounted on said guide rods, means for actuating said cross head, and a pump rod connected to said cross head, substantially as described.

7. In a working head for pumps, the combination, with a base having inlet and discharge openings, a supporting frame pivotally mounted on said base and guide rods rigidly mounted on said supporting frame, of a cross head reciprocally mounted on said guide rods and having an aperture therein,

means for actuating said cross head, a pump rod, and detachable means for securing said pump rod within said aperture.

8. In a working head for pumps, the combination, with a base having inlet and discharge openings, a supporting frame pivotally mounted on said base, and guide rods rigidly mounted on said supporting frame, of a cross head reciprocally mounted on said 10 guide rods and comprising two members, a socket formed in said cross head between said members, a pump rod adapted to be inserted in said socket, means for detachably connecting said members to secure said 15 pump rod within said socket, and means for actuating said cross head, substantially as described.

9. In a working head for pumps, the combination, with the base having inlet and discharge openings, a substantially semicircular supporting frame extending around said base and pivotally supported on said base near the central portion of said supporting frame, and guide rods rigidly secured in 25 the opposite ends of said supporting frame, of a cross head reciprocally mounted on said guide rods, a pump rod detachably connected to said cross head, and means for actuating said cross head, substantially as described.

10. A working head for pumps comprising a base having an internal shoulder near one end thereof, a discharge passage above said shoulder, a supporting plate carried by 35 said shoulder, a suction pipe supported by said supporting plate, a cap adapted to close the upper end of said base, a downwardly extending sleeve carried by said cap, arms secured to said sleeve and adapted to 40 engage said supporting plate to retain the same upon said shoulder when the cap is in position upon said base, a pump rod extending through said supporting plate and through said cap, and means for actuating said pump rod, substantially as described.

11. In a working head for pumps, the combination, with the base having an internal shoulder near the upper end thereof and a discharge passage above the same, a 50 supporting plate carried by said shoulder, a suction pipe supported by said supporting plate, a closure for the upper end of said base, and means carried by said closure for retaining said supporting plate on said shoulder, a supporting frame pivotally mounted on said base, and guide rods rigidly secured to said supporting frame, of a cross head reciprocally mounted upon said guide rods and comprising two members having a 55 socket formed between them, a pump rod having its upper end adapted to engage said socket, means for detachably connecting said members to secure said pump rod within said socket, and means for actuating said 60 cross head, substantially as described.

12. In a working head for pumps, the combination, with the base having inlet and discharge openings, and guide rods supported on said base, of a cross head comprising two members, a plurality of apertures extending through said cross head, each aperture being formed partly in each member of the cross head, two of said apertures being adapted to receive said guide rods, and one of said apertures being adapted to receive the pump rod, means for detachably connecting the two members of said cross head, and means for actuating said cross head, substantially as described.

13. In a working head for pumps, the combination, with a base having inlet and discharge openings, a pump rod, a cross-head attached to and detachable from said pump rod, and means for actuating said cross-head, of a guide for said cross-head, 85 and a support for said guide movably mounted on said base, whereby said cross-head may be moved out of alinement with said base.

14. In a working head for pumps, the combination, with a base having inlet and discharge openings, a pump rod, a cross-head detachably connected to said pump rod, and means for actuating said cross-head, of a guide for said cross-head, and a support 95 for said guide pivoted to said base, whereby said cross-head may be swung out of alinement with said base.

15. In a working head for pumps, the combination, with a base having inlet and discharge opening, a pump rod, and a supporting frame pivotally mounted on said base at one side thereof and extending on the opposite sides of said pump rod, of a guide rigidly secured to said frame, a cross-head detachably connected to said pump rod and having a guideway adapted to coöperate with said guide, and means for actuating said cross-head, whereby upon the movement of said frame about its pivotal center 105 said frame, said guide and said cross-head will be moved out of alinement with said base.

16. In a working head for pumps, the combination, with a base having inlet and 115 discharge openings, a supporting frame pivotally mounted on said base, means for rigidly securing said frame to said base, and a pump rod, of a guide rigidly secured to said frame, a cross-head connected to said 120 pump rod and having a guideway adapted to coöperate with said guide, and means for actuating said cross-head, whereby upon the movement of said frame about its pivotal center the same and the parts carried thereby 125 will be moved out of alinement with said base.

17. In a working head for pumps, the combination, with a base having inlet and discharge openings, a supporting frame piv- 130

totally mounted on said base and a guide rigidly mounted on said supporting frame, of a cross-head reciprocally mounted on said guide and having an aperture therein, means for actuating said cross-head, a pump rod, and detachable means for securing said pump rod within said aperture.

cross-head, of a guide on which said cross-head is mounted, and a support for said guide hinged to said base, whereby said cross-head may be tilted out of alinement with said base. 15

In testimony whereof, I affix my signature in presence of two witnesses.
